UNITED STATES PATENT OFFICE

162,101

CARVING BOARD

Horace P. Wells, South Bend, Ind.

Application May 6, 1949, Serial No. 2,472

Term of patent 14 years

(Cl. D44—1)

To all whom it may concern:

Be it known that I, Horace P. Wells, a citizen of the United States, residing at South Bend, in the county of St. Joseph, State of Indiana, have invented a new, original, and ornamental Design for a Carving Board, of which the following is a specification, reference being had to the accompanying drawing, forming part thereof.

Fig. 1 is a top perspective view of the carving board, embodying my new design.

Fig. 2 is a top plan view of the carving board.

Fig. 3 is a side edge view of the carving board.

I claim:

The ornamental design for a carving board, as shown.

HORACE P. WELLS.
